UNITED STATES PATENT OFFICE.

JOHN WILBUR TIERNEY, OF ASHTREE, AND FRANK HILLS, OF UPTON, LONDON, ENGLAND.

PNEUMATIC DRILLING-MACHINE.

1,393,852.

Specification of Letters Patent. Patented Oct. 18, 1921.

Application filed September 27, 1920. Serial No. 413,164.

To all whom it may concern:

Be it known that we, JOHN WILBUR TIERNEY, a citizen of the United States of America, residing at Ashtree, Beulah Hill, Norwood, in the county of Surrey, England, and FRANK HILLS, a subject of the King of Great Britain, residing at 210 Neville road, Upton, London, England, have invented certain new and useful Improvements in or Relating to Pneumatic Drilling-Machines, of which the following is a specification.

The present invention relates to pneumatic drilling machines and more particularly to the means used for exhausting air therefrom and is especially applicable to pneumatic drilling machines of the portable type.

According to this invention, a device is provided whereby the escape of the live air which leaks past the pistons and valves into the free chambers of such a machine is effected through and controlled by the throttle handle so as to insure a free exhaust of the said live air when the said machine is in operation and so as to close the said exhaust and prevent any escape of lubricant therefrom when the said machine is not in use. The aforesaid device may consist of a number of suitably arranged holes or vents and passages which are adapted to put the crank chamber and other free air chambers of the machine in communication with the throttle handle thereof and which are arranged so that communication to atmosphere of these free air chambers is controlled by means of the throttle sleeve.

The above-mentioned holes or vents which may be conveniently drilled in the casing of the machine, may advantageously be drilled to the level of the upper part of the valves and made to communicate with a smaller hole or vent provided in the upper part of the valve chambers in order to prevent any leaking and accumulating air from exerting an end thrust on the said valves. The inter-communicating passages provided in the throttle handle may be arranged so as to operate in conjunction with a suitable slot or the like adapted to be controlled by a suitably shaped and dimensioned groove in the throttle sleeve so that when the throttle is in the open position the aforesaid vent holes and passages are open to a free exhaust, and when the said throttle sleeve is turned in the appropriate direction the said

vent holes and passages as well as the air inlet are closed.

In order that the said invention may be clearly understood and readily carried into effect, the same will now be described more fully with reference to the accompanying drawings in which—

Figure 1 is a vertical section taken through a pneumatic drilling machine constructed in accordance with our invention.

Fig. 2 is a horizontal section showing the cylinders and the arrangement of the passages in the throttle.

Fig. 3 is a section drawn to a larger scale taken along the line 2—2 of Fig. 2, and

Figs. 4 and 5 are respectively vertical sections drawn to a larger scale taken along the lines 4—4 and 5—5 of Fig. 1.

A is the casing of the machine B—B are the holes or vents drilled in the casing A and communicating with the crank chamber ⁷⁵ *a* and other free air chambers of the machine. The said holes or vents B, B also communicate with the smaller holes or vents C, C provided in the upper part of the valve chambers D, D (see Fig. 3) in order to prevent any leaking and accumulating air from exerting an end thrust on the valves *d* *d*. The said holes or vents B, B communicate with the throttle handle E through the passages *b* *b* (see Figs. 1, 2 and 4) which lead to the passages *b* ^x *b* ^x that communicate through the transverse passage *e*. The said throttle handle E is formed with the three passages *e*', *e* ², *e* ³ for the admission and exhaust of the operating fluid which is controlled by the sleeve F which constitutes the throttle proper and is adapted to be rotated upon the throttle handle E. The said sleeve F is provided with the two passages *f*, *f*' which when the sleeve is in the position shown in the drawing permits the operating fluid to enter the cylinders of the machine through the passages *e*', *f* and *e* ² and exhaust therefrom through the passages *e* ³ and *f*'. If the said sleeve be turned through 90° in the direction of the arrow (see Figs. 4 and 5) the said passages *e* ² and *e* ³ are closed by the said sleeve and the machine becomes inoperative, if the sleeve be further rotated in the same direction through a further 90° the machine becomes operative again but works in the opposite direction as the passages *e*' *e* ³ become inlet passages and the

passages e^2 and f' the exhaust passages. The throttle handle is slotted at the said intercommunicating passage e as shown at e^4 and the sleeve F is cut away to form a slot f^2 (see Figs. 2 and 4) so that when the machine is operating that is to say when the sleeve F is turned to admit the operating fluid as shown in the drawing, the said holes or vents B are open to the atmosphere and when the sleeve F is turned to cut off the supply of operating fluid the said intercommunicating passage e is closed by the walls of the sleeve F , thereby preventing any leaking of lubricating oil from the machine when the latter is lying idle. The said holes or vents operate as aforesaid whether the machine is running in a clock-wise or anti-clockwise direction according to the position of the said sleeve F . In some cases the exhaust from the said holes or vents may be independent of the main exhaust of the machine.

A device in accordance with the present invention insures that the leaking live air is effectively exhausted and guards against the danger of any back pressure taking place owing to an undue accumulation of air in the casing of the machine. The said device further insures that no lubricating oil is blown to atmosphere, or leaks away when the machine is not in use, as is the case with certain exhausting devices which have been hitherto employed. Furthermore when the machine is used for submarine work excessive bubbling is avoided as the leaking live air instead of escaping through the joints of the casing of the machine and causing inconvenience to the diver passes up the exhaust pipe with which such machines are provided.

What we claim and desire to secure by Letters Patent of the United States is:—

1. In a pneumatic drilling machine, the combination of a throttle handle having passages communicating with the free air spaces of the machine, means for placing such passages in communication with the atmosphere, and means for closing such passages.

50 2. In a pneumatic drilling machine, the combination of a throttle handle, having passages communicating with the free air

spaces and valve chambers of the machine, means for placing such passages in communication with the atmosphere, and means for closing such passages.

3. In a pneumatic drilling machine, the combination of a throttle handle, having passages communicating with the free air spaces of the machine, means for simultaneously opening the main inlet of the machine and placing said passages in communication with the atmosphere, and means for simultaneously closing said inlet and closing said passages.

4. In a pneumatic drilling machine, the combination of a throttle handle, having passages communicating with the free air spaces and valve chambers of the machine, means for simultaneously opening the main inlet of the machine and placing said passages in communication with the atmosphere, and means for simultaneously closing said inlet and closing said passages.

5. In a pneumatic drilling machine, the combination of a throttle handle having a slot therein and communications therethrough between said slot and the free air spaces of the machine, a throttle sleeve rotatable in relation to said throttle handle to open and close the main inlet of the machine, the said sleeve comprising an outlet to the atmosphere and a groove communicating with said outlet, said groove being in register with said slot when said sleeve opens said inlet and being withdrawn from said slot when said sleeve closes said inlet.

6. In a pneumatic drilling machine, the combination of a throttle handle having a slot therein and communications therethrough between said slot and the free air spaces and valve chambers of the machine, a throttle sleeve rotatable in relation to said throttle handle to open and close the main inlet of the machine, the said sleeve comprising an outlet to the atmosphere and a groove communicating with said outlet, said groove being in register with said slot when said sleeve opens said inlet and being withdrawn from said slot when said sleeve closes said inlet.

JOHN WILBUR TIERNEY,
FRANK HILLS.
